GOLF-TEE HOLDER.

Application filed December 12, 1925. Serial No. 75,059.

This invention relates to holders especially adapted for use in carrying golf tees.

Briefly stated an important object of this invention is to provide a golf tee holder having simple means whereby a number of golf tees may be inserted into openings provided for that purpose and held therein by friction so that the person wearing the holder will not cause the golf tees to work out of place as a result of the body movement necessary in playing golf.

A further and equally important object is to provide a golf tee holder of the character specified which may be employed in connection with a belt, a golf bag, a hat, a separate special receptacle or the like.

Other objects and advantages will be apparent during the course of the following description:

20 In the accompanying drawing forming a part of this application and in which like numerals are employed to designate like parts throughout the same,

25 Figure 1 is a perspective of a golf tee holder in the form of a special receptacle which may be carried in one's pocket or pocketbook; Figure 2 is a section on the line 2—2 of Figure 1, and Figure 3 is a section on the line 3—3 of Figure 1.

30 The drawing illustrates the improved holder constructed in the form of a special folder having front and back flaps 36 and 38 adapted to be joined at the corners thereof by two-part fasteners 40. A strip 43 may be stitched or otherwise secured to the back flap 36 to define a plurality of pockets 12 for the reception of the shanks of the golf tees. It will be seen that the upper edge of the strip 43 is spaced below the free edge of the flap 36 so that the heads of the golf tees will be positioned entirely within the special folder.

The shanks of the headed golf tees 11 are inserted in the upper open ends 13 of the pockets 12 with the heads frictionally engaging the back flap 38 so that the tees will not tend to work loose from the device.

The fastenings 40 at either end of the flaps

36, 38 tend to hold the flap 38 in frictional engagement with the heads of the tees. However, it will be clear that the flaps 36 and 38 can be separated slightly for the withdrawal of a tee without making it necessary to unfasten the fasteners 40. The two fasteners 40, as previously stated, tend to draw the upper portion of flap 38 against the heads of the tees,—in this respect cooperating to the upper portion of the flap 36 which is extended above the pocket defining strip 43.

Having thus described the invention what is claimed is:—

A golf tee carrier comprising a body portion including two flaps connected along one longitudinal edge and adapted to be folded one upon the other, cooperating fastening elements associated with the corners of said flaps adjacent the outer edges thereof whereby to tend to hold the flaps in close contact at their outer edges, a strip disposed upon the inner surface of one of said flaps and below the outer edge thereof and substantially aligned with said fasteners, said strip being secured to said flap by means of spaced rows of transverse stitching, said stitching defining pockets for the shanks of relatively large headed golf tees, the length of the heads of said golf tees being less than the distance between the outer edge of said strip and the outer edge of the flap to which it is attached, whereby the heads of said tees will be engaged and supported by the outer portion of said strip carrying flap at all times, the inner surface of the other flap adjacent its outer margin engaging said head when the fasteners are connected whereby the outer flap cooperates in holding the tees in place, and one of said flaps being relatively flexible whereby the inner surfaces of the flaps at the outer edges thereof can be separated without undoing the fasteners when it is desired to remove a tee from one of the pockets.

In testimony whereof we affix our signatures.
